UNITED STATES PATENT OFFICE.

HUGO SCHUBERTH, OF ROMBACH, GERMANY.

MECHANICAL COOLING-BED FOR ROLLING-MILL TRAINS.

1,115,869.

Specification of Letters Patent.

Patented Nov. 3, 1914.

Application filed July 16, 1912. Serial No. 709,756.

To all whom it may concern:

Be it known that I, HUGO SCHUBERTH, a subject of the King of Saxony, residing at 3 Metzerstrasse, Rombach, Germany, have invented certain new and useful Improvements in Mechanical Cooling-Beds for Rolling-Mill Trains; and I do hereby declare the following to be a full, clear, and exact description of the invention, such as will enable others skilled in the art to which it appertains to make and use the same.

In iron rolling mills for rolling iron of small size having a delivery-trough and a lateral cooling bed, it has not been possible hitherto to utilize the full capacity of the rolls, because it was necessary to await the complete delivery and lifting of the rolled material on to the cooling bed after each pass before being able to allow the material rolled in the next following pass to enter the delivery-trough.

The present invention has for its object to enable a rolling mill to be utilized to its full capacity by providing the cooling bed with two or more feed ways which can be charged and discharged independently of each other. By this means it is possible to increase the output of the rolling train very considerably.

Several forms of apparatus constructed according to this invention are illustrated by way of example in the accompanying drawings in which:

Figures 1 to 4 are sectional end elevations each showing one form of the improved apparatus. Fig. 5 is a side elevation to Fig. 2 of the feed ways. Fig. 5^a is a cross section thereof. Fig. 6 is a sectional end elevation of a somewhat different relative disposition of the cooling bed and the feed ways showing a form the operation of which is the same as that shown in Fig. 2.

In Fig. 1, as also in the following figures, a' and a^2 are two feed ways constructed in the usual manner as live roller beds for the straightening bench c ; r' and r^2 are the live rollers of the feed ways. w' is the material which is handled by the feed way a' , and w^2 is the material which is handled by the feed way a^2 . The transference of the material w' from the feed way a' is effected in the usual manner by a conveyer rake t which is raised and lowered and at the same time moved to-and-fro by one or more eccentrics 3. The said rake lifting the material from the feed way a' on to the draw

bench and at the same time conveying the material lying on the straightening bench to the cooling bed k and conveying them farther along the latter.

The conveyance of the material w^2 arriving on the second feed way a^2 is effected in the form shown in Fig. 1 as follows: b is a tilting axle actuated by worm gearing s or other driving means from an electric motor or other engine. On this axle b is mounted a fork g which lifts the material w^2 from the feed way a^2 over the feed way a' to the straightening bench c of the lateral cooling bed k whence the said material is conveyed away together with the material w' by the conveyer rakes t , while the fork g moves back into its original position. The basic idea of this operation is thus a tilting of the feed way a^2 or rather of the forks g which constitute its sections over the feed way a' around the tilting axle b . The shape of the forks is determined by the operation. The material remains at rest until almost the end of the tilting movement and then it slides down the inclined arm g' of the fork and is directed into its proper position by the projecting beak g^2 of the forks.

The entire arrangement is very simple. The feed ways are on the same level, and their rollers r' and r^2 are mounted on the same axis, being driven by a common roller-driving device.

In the modification shown in Fig. 2 the mechanism for transferring the material w' to the cooling bed is similar to that shown in Fig. 1. The material is transferred from the feed way a^2 by the following apparatus. The lever h which is driven by the crank d and is guided by a radius rod f describes with the blades i attached to its end a closed curve l , so that the material w^2 is lifted by the blades from the feed way a^2 and conveyed over the straightening bench c . At this place it is removed from the blades by the strippers m during the return movement and conveyed to the straightening bench. In this apparatus the feed ways may be arranged in step-fashion as shown in Fig. 2, for the purpose of affording a free path for the movement of the blades. The rollers r' and r^2 (see Figs. 5 and 5^a) when driven by a common driving device have different diameters but equal peripheral speeds, this can be easily effected by suitably proportioning the bevel gearing p' and p^2 . The strippers m which may also be forked,

are so connected to a lever 5 driven by a cam 4, that as soon the rakes t begin their elevating stroke the said strippers move under the straightening-bench, ready to resume 5 their former position as soon as the rakes have finished their elevating stroke.

In cases where as shown in Fig. 6, the cooling bed k is situated on a higher level than the floor of the feed way a' so that 10 the blades can move freely back over the feed way a' the strippers m can be dispensed with. The material w' is lifted by a 15 rake as in the other forms shown, the said rake having a greater up-and-down movement than in Fig. 2.

In the form shown in Fig. 3 the lifting of the material w^2 is effected by lever mechanism u pivoting on a center q and adapted to be temporarily inclined by means of the 20 intermediate parts v , w , y by crank mechanism z to such an extent as to allow the material to slide off the mechanism u on to conveyer levers 6 over the feed way a' , whereupon it is stopped by stops n on the 25 straightening-bench c . In this case also the stops dip under the straightening-bench during the stroke of the conveyer rakes t , while the conveyer lever 6 is being raised.

In the modification shown in Fig. 4 the 30 materials w' and w^2 have a common delivery trough 2 but they are kept strictly apart by double-coned live rollers r so that each of the two materials w' , w^2 has its own feed way a' , a^2 respectively. The lifting of the 35 material w^2 on to the cooling bed k is effected by the blade device i which is (described above with reference to Fig. 2) operated by means of guide link motion h , f with the only difference that the curve l is an open 40 curve and therefore the blades follow the same path in coming as in going.

I claim:

1. A mechanical cooling bed for rolling mill trains, comprising a plurality of feed- 45 ways for the rolled material, and means by

which said feedways can be independently charged and discharged, the rolled material being passed by said means from said feedways to said cooling bed.

2. A mechanical cooling bed for rolling 50 mill trains, comprising a plurality of feedways for the rolled material, a cooling bed alongside of one feedway, and a tilting lever-mechanism by which the rolled material is transferred from one feedway over the 55 other to the cooling bed.

3. A mechanical cooling bed for rolling 60 mill trains, comprising a plurality of feedways, a cooling bed sideways of one feedway, a straightening bench and a tilting lever-mechanism for transferring the material from one feedway over the other feedway to the cooling bed and straightening bench.

4. A mechanical cooling bed for rolling 65 mill trains, comprising a plurality of feedways, a straightening-bench alongside of one feedway, a tilting lever-mechanism whereby the material is conducted from one feedway over the second feedway to the straightening-bench, a cooling bed, and vertically and 70 horizontally reciprocating conveyer-rakes alongside of the straightening-bench and cooling bed.

5. A mechanical cooling bed for rolling 75 mill trains, comprising a plurality of feedways for the rolled material, said feedways being independently charged and discharged, a tilting lever-mechanism by which the rolled material can be lifted from one feedway to the cooling bed, and strippers 80 for removing the rolled material from said tilting lever-mechanism onto said cooling bed.

In testimony that I claim the foregoing as my invention, I have signed my name in 85 presence of two subscribing witnesses.

HUGO SCHUBERTH.
